(57) **CLAIM**

The ornamental design for a bowl, as shown and described.

DESCRIPTION

FIG. 1 is a top perspective view of a bowl showing our new design;

FIG. 2 is a left side elevation thereof shown on a slightly reduced scale;

FIG. 3 is a right side elevation thereof;

FIG. 4 is a front elevation thereof;

FIG. 5 is a rear elevation thereof;

FIG. 6 is a top plan view thereof; and,

FIG. 7 is a bottom plan view thereof.

This design is not limited to the exact details shown in the drawings, since equivalents and colorable imitations thereof will be evident to a person of ordinary skill in the art. Thus, within the scope of the appended claim, which is intended to cover only the ornamental and novel elements shown in the drawings, the invention may be practiced otherwise than as specifically shown and described herein.
